(57) CLAIM

The ornamental design for a gazebo having inserts with mirror spear design, as shown and described.

DESCRIPTION

FIG. 1 is a perspective view of a gazebo having inserts with mirror spear design, showing my new design;

FIG. 2 is a bottom plan view thereof;

FIG. 3 is a bottom plan view thereof;

FIG. 4 is a side elevational view thereof, all of the sides being identical;

FIG. 5 is a perspective view of a second embodiment of a gazebo having inserts with mirror spear design, showing my design;

FIG. 6 is a top plan view thereof;

FIG. 7 is a bottom plan view thereof; and,

FIG. 8 is a side elevational view thereof, all the sides being identical.
